CARL RUDOLPH KRONE, OF OAKLAND, CALIFORNIA.

MATCH-BOX HOLDER.

Application filed November 24, 1926. Serial No. 150,433.

The present invention relates to improvements in match box holders, and its particular object is to provide a holding or retaining element in combination with the ordinary 5 match box, consisting of a casing and a drawer free to slide therein and dimensioned identically whether manufactured in Sweden, 10 Belgium or America. My invention being a holder embraces certain parts of the casing without covering the friction surfaces, and being a retaining element it tends to prevent casual discharge of the drawer and replaces the drawer after use automatically by means of an elastic band cooperating and 15 interlocking therewith. A further object of this invention is to combine with this holder or retaining element structural means adapted to position and hold the elastic band in a central and longitudinal relation 20 as to the holder and to the match box. Further objects and advantages of my invention will appear as the specification proceeds.

The preferred form of my invention, in various stages of development, is illustrated 25 in the accompanying drawing in which—

Figure 1 shows a perspective view of a match box having my holder in its simplest form attached thereto,

Figure 2 a longitudinal vertical section thru a match box having a more advanced form of holder, and an elastic band interlocked with the holder attached thereto,

Figure 3 a bottom plan view of the holder used in Figure 2,

Figure 4 a plan view of a blank out of which the holder is made,

Figure 5 a bottom plan view of a further advanced form,

Figure 6 a longitudinal section thru a match box having the holder of Figure 5 attached thereto,

Figure 7 an end view of the same combination,

Figure 8 an end view of the same having end flanges, and

Figure 9 a plan view of a blank out of which the holder of Figure 8 with end flanges is made.

While describing preferred forms of 50 this invention, I reserve the right to make changes or structural modifications within the scope of the claims hereto attached.

A match box 1 as in common use comprises a casing 2 and a sliding drawer 3, and the

simplest form of my holder 4 shown in Figure 1 comprises a metal plate 6 having marginal portions bent as at 5 and extended therefrom so as to provide the resilient flanges 7 which support the corners and sides of the casing in contact therewith.

A central longitudinal portion of the plate 6 is shaped to form the groove 8, the inner flat face of which bears upon the casing, while its transversely curved longitudinal margins are adapted to increase the resiliency of the clamping action of the flanges 7, exerted upon the casing, provided the holder is dimensioned so that it requires the application of gentle force to press the match box into the holder and to securely hold it in place. A proportionate pressure is transferred by the casing upon the side of the drawer 3 securing the same against casual sliding motion. This security may be increased by surrounding holder and box 75 with an elastic band longitudinally which band finds its seat provided by the groove 8 of Figure 1.

In the form shown in Figures 2 to 4, I provide near the ends of the groove 11 two 80 triangular apertures 12 into which the elastic band 9 may be slipped thru a reduced passage or entrance 13 formed between the lips 14 which are designed to protect the elastic 85 band 9 against casual loss or injury as it encircles the box, elastically preventing the drawer from casual discharge from the box. The Figure 4 shows the details of a blank 16 useful toward stamping such a plate between suitable dies.

As disclosed in Figures 5 to 7, the idea is advanced again. Small transverse slits 17 are provided in the holder 18 near opposite ends thereof while the material between the slits and the ends thereof is shaped to form 95 grooves 19 in which the elastic band 9 may be imbedded. In the material between the two slits 17 a longitudinal cut is made as at 21 and a narrow strip thereof is removed but is compensated for by the contour of 100 the grooves 19, establishing contact between edges of the cut as at 21 and rendering the plate of the holder continuous except for the slits 17 which remain open. Still the slits 17 with the cut as at 21 define a tongue 22 105 adapted to be projected beyond the plate outwardly so as to open a gap by bending the plate over the grooves 19 sufficiently to

permit the elastic to pass through it and enter the slits. The gap is closed by reversed action securing the elastic against casual loss.

5 As disclosed in Figures 8 and 9, in combination with the described forms, additional end flanges 7' are provided to cover parts of the end edges of the casing thereby to confine the same within the tray of the holder 10 against sliding with the drawer when the box is being opened in the usual manner in order to expose its contents. In Figure 9 is disclosed a blank 20 to be used for stamping the holder of Figure 5 with end flanges between suitable dies.

Suitable elastic loops are made for the market and the groove 8 of Figure 1 indicates a proper seat for one. The use of elastic bands makes this invention a delightfully animated thing, as they slip naturally into prepared places.

The assembled box and holder may be held between thumb and second finger and opened by applying the tip of the index finger to the presenting wall of the drawer. When the finger is withdrawn the elastic reacts, the drawer rebounds and the box is closed. The state of elastic rest of the band prevents casual opening of the box and spilling of 30 contents other than matches.

The manner of using my invention will be understood from the foregoing description. The holder as illustrated in Figure 1 is applied to the match box by pressing it on until the angles formed by the bottom and the sides of the latter are in contact with and rest upon the inner surface of curved portions 5 of the former connecting the bottom and both sides of the tray or holder 4 40 closed in Figure 1 as the plate 6 and the flanges 7.

In cooperation with the contour of the groove 8, which reinforces longitudinally the bottom of the match box at its middle portion, and with the curved portions 5, the flanges 7 exert a continuous lateral pressure upon the sides of the match box increasing thereby the frictional resistance usually offered to the sliding movement of the drawer 50 within the same. Of course, if the friction surfaces of the sides of the match box are to some extent in contact with the flanges 7 the resistance to a sliding motion of the casing 2 within the holder 4 is quite considerably increased. If an elastic is lodged in the groove 8, so as to surround the combination of match box and holder the casual sliding out of the drawer from the box is inhibited.

60 In the form disclosed by Figures 2 to 4 the principle and method of attachment between holder and box are identical with those of Figure 1. The groove 11 however does not extend through the plate of the holder but is terminated by triangular aper-

tures based vertically across the same the apices of which are provided with narrow channels through the short edges of the holder at 13 to compensate for the material used in shaping the groove. The lips 14 are adapted to close the gap at 13. By bending the plate of the holder outwardly over the groove 11 the gap is opened sufficiently to allow the elastic to be snapped into the apertures 12 and to lie in the groove 11 so as to be stretched over the match box to complete its appointed functions.

In the form disclosed by Figures 5 to 7 the principle and method of attachment between holders and box are identically those of Figure 1, but terminal grooves 19 are provided to bear upon terminal parts of the casing and to adjust the elastic, which extends from one groove to the other in a free space extending between them and between the casing and the holder, and it remains to describe the manner by which the elastic is placed into the covered passage. To do so, the holder is held by its flanges between the thumb and the second finger while the index is applied to the trough side of the holder from below, whereupon the flanges are carefully pressed one toward the other. It will be observed that the metal bends over the grooves 19, slightly flattening the same, and

that the free edge of the tongue 22 is projected beyond the plane of the holder outwardly and that thereby the slit as at 21 is opened sufficiently to permit the elastic to pass between the tongue and the plate of the holder into the slits 17. If two holders are applied to one box, as indicated in drawings Figure 6 and Figure 7, the process is, with the same elastic, repeated. After the elastic has been adjusted to both holders one holder is made to face the other, trough to trough, and the closed match box is pressed into the troughs, and any twisting of the elastic may be adjusted. It will not be necessary to remove the casing as long as its friction service is satisfactory because the elastic can be stretched over one side of the box and then the drawer removed, refilled or replaced.

In the form disclosed by Figures 8 and 9 the principle and method of attachment between holder and box are identically as those of Figure 1.

All the forms differ one from the other only in the application of structural finesse and I may be permitted to state that the same finesse may be applied to all-metal boxes having a flanged lid and a drawer and dimensions to fit other needs.

I claim:

1. A match box holder of the character described, comprising a tray adapted to support contiguous corners and sides of a match box casing therein, a middle portion of the tray being molded longitudinally to bear against the bottom of the match box, and an

elastic encircling the casing and being held to said middle portion against lateral slipping.

2. A match box holder of the character described, comprising a tray adapted to embrace contiguous surfaces of a match box casing therein, a middle portion of the tray shaped to form a groove the curved longitudinal margins of which with the rigid members of the tray effect a clamping action of the holder upon the match box when the latter is gently forced into the former, and an elastic encircling the casing and being held to said middle portion against lateral slipping.

3. A match box holder of the character described, comprising a tray adapted to embrace contiguous portions of a match box casing therein, a middle portion of the tray shaped to form a groove, adapted to supply means to effect a clamping action of the holder upon the match box and an elastic band, to lie in the groove, adapted to be stretched over the match box casing and over the ends of the drawer within the casing and adapted to permit spontaneously the purposed protruding of the ends of the drawer for exposing its contents and adapted to spontaneously return the ends of the drawer within the casing when the cause for protrusion has ceased to act.

4. A match box holder as defined in claim 3 having apertures and means for holding the elastic in position therein.

5. A match box holder of the character described, comprising a plate having marginal portions bent and extended therefrom so as to form a tray and having a measured strip of plate material removed from its middle portion leaving a longitudinal slot between

intact end portions of the tray, and having these intact end portions shaped into short longitudinal grooves adapted to compensate for the removed material and to bring the edges of the said slot close together thereby rendering the plate all but continuous of surface excepting a crosscut separating each groove from the plane of the plate.

6. A match box holder as defined in claim 5 in which the edges of the slot are adapted to be separated sufficiently to allow an elastic band to be passed between them and to lie in the grooves and upon the inner surface of the holder and thereby to be held against lateral shifting.

7. A match box holder of the character described, comprising a reinforcing element adapted to be placed against a face of a match box having end sections indented longitudinally and being formed with a longitudinal slit between the indentations allowing the intermediate section to be bent out of the plane of the element by exerting simultaneous pressure upon the opposite margins thereof in a direction vertically across the longitudinal slit thereof.

8. In combination, a casing, a drawer free to slide therein, a reinforcing element lying against the outer face of the casing and an elastic band locked in the reinforcing element against lateral shifting and adapted to stretch over the casing for holding the drawer therein against casual removal therefrom also adapted to permit useful part-way sliding therefrom and furthermore adapted to reinstate the drawer to the tenure of the casing automatically when the useful cause has ceased to act.

In testimony whereof I affix my signature.
CARL RUDOLPH KRONE.
